UNITED STATES PATENT OFFICE.

MYRON COSSEY, OF BROOKLYN, NEW YORK, ASSIGNOR TO RELIANCE BALL BEARING DOOR HANGER CO., OF NEW YORK, N. Y., A CORPORATION OF NEW YORK.

DRAWER-SLIDE.

1,045,523.

Specification of Letters Patent. Patented Nov. 26, 1912.

Application filed April 3, 1911. Serial No. 618,746.

To all whom it may concern:

Be it known that I, MYRON COSSEY, a citizen of the United States, and resident of the borough of Brooklyn, county of Kings, 5 and State of New York, have invented certain new and useful Improvements in Drawer-Slides, of which the following is a specification.

It has been my purpose to improve the 10 construction of the means used for guiding and supporting drawers and similar devices so that they may easily and accurately slide into place.

One of the objects of the invention is to 15 provide a drawer with anti-friction sliding means which will permit perfectly free movement longitudinally, but which will prevent movement in other directions which might result in binding.

20 Another object has been to produce the anti-friction slide in such form that it can be easily and cheaply made in light form but of sufficient strength to stand the strains of practical use.

25 The novel features of the invention will be apparent from the following description, taken in connection with the accompanying drawings.

In the drawings Figure 1 is a cross section of a portion of the drawer and casing having the preferred form of my drawer slide applied thereto; Fig. 2 is a detail perspective view of the ball spacing and retaining means; Fig. 3 is a side view of a portion of the slide; Fig. 4 is a side view of the drawer and casing having my preferred form applied thereto, the drawer being pulled open; Fig. 5 is an end view of the preferred form of my slide showing the limiting stops; and Fig. 6 is a side view of the track members showing the limiting stops in operation. Fig. 7 is a sectional view of a modified arrangement of the slide.

In Fig. 1 I have shown a casing 1, which 45 may be a desk or similar article of furniture, which is provided with an ordinary drawer 2. These parts are usually made of wood and the side wall of the drawer is spaced from the corresponding side wall of the casing sufficiently to receive my improved slide. In the preferred form, my slide is made up of two track members formed from sheet metal, preferably drawn steel. As will be seen by reference to Fig. 1, the track mem-

ber 3 is made substantially U-shaped in 55 cross section and it extends longitudinally of the drawer casing at the side from the front to the rear of that casing, being held in place by screws 4 which pass through holes in the bottom of the U-shaped portion leaving substantially horizontal flanges projecting outward from the wall of the casing. 60 These flanges or edges are rolled or bent so as to form outwardly facing grooves 5 and 6. A movable track member 7 of sheet 65 metal is also formed substantially U-shaped in cross section, but of sufficient width to make its flanges or free edges fit over and embrace the flanges of the fixed track 3. The free edges of the movable track are 70 bent or rolled outwardly so as to leave inwardly facing grooves 8 and 9 which register with the grooves 5 and 6. The outward bends leave shoulders 10 and 11 on the interior of the movable tracks 7, and a movable ball retainer 12 preferably made of steel fits loosely between the shoulders 10 and 11 and slides freely longitudinally within the movable track 7. This retainer is also U-shaped in cross section fitting over 75 and embracing the fixed track 3 loosely, and provided with holes 13, Fig. 3 to receive the balls 14 moving in the registering grooves of the two tracks. This retainer serves to properly space the balls and to hold them in 80 position, and it will be understood that it moves along the track with the balls. At the ends of the fixed track 3, I place the strengthening filler blocks 15, these blocks fitting between the side flanges and being 85 held in place by the screws 16. A pin 17 projects from the face of this block almost to the rear wall of the movable track 7 standing in the path of the spacer 12. This pin 17 may be in the form of a screw passed 90 through the fixed track 3, and the block 15. At each end of the movable track 7 a pin 18 is placed projecting inward in the path 95 of the retainer 12. These pins 17 and 18 serve as stops to limit the movement of the track 7 on the track 3, because when the pin 17 at the front end of the fixed track 3 is struck by the retainer 12, it will prevent any further forward movement of that retainer and its balls and when the pin 18, Fig. 6, 100 strikes the other end of the retainer 12 the movable track 7 cannot move outward any 105

farther. While I have shown the slide only on one side of the drawer it will be understood that a duplicate of this is used on the other side of the drawer, and it will be observed by reference to Fig. 1 that the drawer is supported from the slide by means of a longitudinal strip 19 which may be made of wood held in place by the screws 20. This strip or rail simply rests by gravity on top of the straight upper surface of the movable track 7 and the frictional engagement makes the movable track move forward when the drawer is pulled out, but it will be observed that when the track has moved its full limit, and the stops come into operation, it is still possible to move the drawer making the strip or rail 19 slide on the movable track 7, and thus the drawer can be entirely removed from the casing leaving the anti-friction drawer slides still in position in the casing. The drawer preferably fits closely against the inner straight vertical face of the movable track 7 so that there will be no play or lost motion and the connection between the movable track and fixed track is such that the only relative movement is longitudinal. This will prevent binding and will make the drawer move easily and smoothly into either open or closed position.

It will be observed that the form of slide shown in Fig. 1 can be easily and cheaply made of drawn steel which will be comparatively light and which will at the same time have the requisite strength to stand all the strains of practical use, and it will further be observed that by the construction described the drawer will work easily on the anti-friction bearings under all ordinary operations and that the drawer can be absolutely removed from the casing without disturbing in any way the anti-friction slide.

In Fig. 7 I have shown a modified arrangement in which the parts occupy different relative positions but the structure of the two sliding members and the structure of the ball retainers correspond with that described in connection with Fig. 1. In this modified form the outer slide 21 of sheet metal is secured to the casing 1 by screws 22 and the inner slide member 23 is placed with the open side of the U-shaped cross section facing in the same direction as the member 21 so as to form practically a slot in which 50 slidably and loosely fits the strip 24 secured to the drawer 2. In this instance the drawer is supported through the strip 24 from the member 23 and it is in turn supported by the balls from the fixed member 21 and it 55 will be understood that the strip 24 can slide out beyond the end of the member 23 so that the drawer can be entirely removed just as in the structure shown in Fig. 1.

While I have disclosed a preferred embodiment of my invention it will be under-

stood that the invention in its broader aspect is not limited to the details of construction described and shown.

Having thus described the invention, what is claimed is:

1. The combination with a drawer, of a casing for said drawer, tracks supporting said drawer at the sides having separated grooves facing each other and extending in the direction of movement of said drawer, 70 tracks secured to said casing and provided with oppositely facing grooves registering with the first mentioned grooves, the tracks on the casing and tracks supporting the drawer telescoping one into another, anti-friction balls in each pair of grooves locking the parts against any movement except longitudinal, and integral means engaging the balls in both grooves to hold the same in spaced relation to each other and allowing the simultaneous movement of the balls but holding the same against independent movement.

2. The combination with a drawer, of a casing therefor, a track secured to said casing having oppositely facing longitudinal grooves, a second track movable on the first having grooves facing and registering with said first mentioned grooves, anti-friction balls in said grooves locking said tracks 95 against any relative movement except longitudinal, one piece spacing means for said balls in both grooves to allow simultaneous movement of the balls but to hold the same against independent movement, and said drawer being provided with a part slidably resting on said movable track to support said drawer.

3. The combination with a drawer, of a casing therefor, a track secured to said casing at each side having oppositely facing longitudinal grooves, a second track movable upon each of the first mentioned tracks having grooves facing and registering with said first mentioned grooves, anti-friction balls in said grooves locking said tracks against any relative movement except longitudinal, a spacing means for the balls in both grooves to permit simultaneous movement of said balls but to hold the same 105 against independent movement, and rails on the sides of said drawer frictionally resting on said movable tracks whereby said drawer and tracks will normally move together and said drawer may slide on the 110 track when said track has reached the limit of its movement.

4. The combination in a device of the class described, of two sheet metal track sections substantially U-shaped in cross section 125 fitted together with the free edges overlapping, the said edges being bent to form registering longitudinal grooves, anti-friction balls in said registering grooves locking said sections against any relative move- 130

ment except longitudinal, and a ball retainer U-shaped in cross section fitting within and movable along the outer track and embracing the inner track provided 5 with holes to receive said balls.

5. The combination with a drawer and the like having parts provided with a plurality of oppositely facing longitudinal grooves, a casing for said drawer and the 10 like also having parts provided with a plurality of oppositely facing longitudinal grooves having their open faces arranged adjacent and opposite to the open faces of the grooves on the drawer and the like, 15 a plurality of anti-friction devices arranged in each of the respective adjacent grooves on the drawer and the casing, and means for retaining said anti-friction devices in spaced relation to each other, the grooved 20 parts on the drawer and those on the casing being capable of relative movement between them, and the anti-friction devices acting as retaining devices to hold the drawer and casing in operative position.
- 25 6. The combination with a drawer and the

like having parts provided with a plurality of oppositely facing longitudinal grooves, a casing for said drawer and the like also having parts provided with a plurality of oppositely facing longitudinal grooves having 30 their open faces arranged adjacent and opposite to the open faces of the grooves on the drawer and the like, and a plurality of spaced anti-friction devices arranged in each of the respective adjacent grooves on 35 the drawer and the casing, the grooved parts on the drawer and those on the casing being capable of relative movement between them and the anti-friction devices moving with the movable member, said anti-friction 40 devices also acting as retaining devices to hold the drawer and casing in operative position.

In testimony whereof I affix my signature in presence of two witnesses.

MYRON COSSEY.
